UNITED STATES PATENT OFFICE.

JOHN OLIPHANT McKEAN, OF WESTFIELD, MASSACHUSETTS, ASSIGNOR TO FOSTER MACHINE COMPANY, OF WESTFIELD, MASSACHUSETTS, A CORPORATION OF MAINE.

WINDING-MACHINE.

1,126,808.

Specification of Letters Patent.

Patented Feb. 2, 1915.

Application filed August 6, 1913. Serial No. 783,254.

To all whom it may concern:

Be it known that I, JOHN O. McKEAN, a citizen of the United States, residing at Westfield, in the county of Hampden and 5 State of Massachusetts, have invented new and useful Improvements in Winding-Machines, of which the following is a specification.

My invention relates to winding machines 10 such as are used to wind yarn and the like onto a quill or core, and particularly to winding machines of that class which produce conical cops having the well known self binding "open" wind. Machines of 15 this class have heretofore been so constructed that the completed cop was made with a practically square butt end, that is, with a base end whose surface was perpendicular with relation to the axis of the cop, 20 or substantially so.

As the thread guide of a winding machine of the class specified travels toward the large end of the cop the convolutions are laid progressively more nearly at right 25 angles relatively to the axis of the cop until the base end of the cop is reached whereupon the thread guide reverses its direction of movement and travels back toward the small end of the cop. When the thread 30 guide reverses at the base of the cop there is a momentary dwell of the thread guide during which the yarn is laid onto the base corner of the cop for a substantial distance at practically a right angle relatively to the 35 axis of the cop before the thread guide starts the yarn on its next spiral toward the small end. It will thus be seen that each spiral winding of the cop that is laid thereon by movement of the thread guide toward the 40 base is connected with the next spiral winding that is laid thereon by the immediately following movement of the thread guide toward the small end of the cop, by a portion or strand which lies along the corner or 45 peripheral edge of the cop for a substantial distance. Heretofore this structural peculiarity of the base of a conical "open wind" cop combined with the perpendicular, or substantially perpendicular, relation 50 of said base with the axis of the cop, has resulted in imperfect and insecure winding at said base. The imperfection in the winding was due to the fact that in practice it is impossible for the thread guide to lay each 55 spiral-connecting portion in exactly the po-

sition upon the previously laid spiral connecting portion beneath it, that it should occupy. Sometimes, also, the tension on the yarn as it is being laid displaces previously laid strands beneath it, if they have not been 60 perfectly laid, with an imperfect structure as the result. If carried beyond its proper position, not only does the spiral-connecting portion become a float upon the butt end of the cop through its being free to sag to- 65 toward the axis, but the subsequently laid spiral connecting portions above it are not properly supported and they too are free to sag toward the axis and produce floats or looseness. Likewise a spiral-connecting por- 70 tion laid short of its proper position would not properly support subsequent strands laid upon it, which consequently would be loose, and being under some tension when laid would draw down across the base of 75 the cop. In either case the result would be the formation of loose threads or strands across the base of the cop, from one point to another of the peripheral edge of the cop. Such an imperfection is very objectionable 80 as, in the process of unwinding, the yarn lying across the base, as it is drawn off over the small end tends to pull or lift the cop, putting a sudden strain upon the yarn which results in breakage and snarling of 85 the latter.

The object of my invention is to provide an improved winding machine which will obviate the objections noted and it consists of a winding machine so constructed that 90 the yarn being wound onto the cop generates a force which is used to vary the relation between the thread guide and cop as the winding operation progresses so that each succeeding spiral-connecting portion 95 or strand at the base of the cop is laid short of the position occupied by the previously laid spiral-connecting portion beneath it. This results in the spiral-connecting portions of the base of the cop occupying a 100 shelfed relation so that the base of said cop is crowned and the objections above noted are obviated.

In the accompanying drawings: Figure 1 is a partial front elevation of a winding machine embodying one form of my invention; Fig. 2 is a side elevation of the mechanism shown in Fig. 1; and Fig. 3 is an elevation of a cop such as is produced by the machine.

Having reference to the drawings, 1, 1, 110

represent two posts forming part of the frame of the machine and on these posts is journaled a shaft, 2, carrying a cop driving drum, 3. Above drum 3 is arranged a quill 5 or core holding mandrel, 4, rotatably secured to a spindle, 5, whereof one end is fastened to a yoke, 6, pivotally connected at 7, to the lower end of a link 8. At its upper end the link 8 is pivotally connected at 9, to a bracket 10, rigidly fastened by a screw 11, to a fixed bar 12, forming part of the frame of the machine. The yoke 6, is in the form of a right angle and its outer bifurcated end straddles the end of spindle 5, and is pivotally connected therewith by a bolt, 13. A spring 14, secured to the yoke 6, normally holds spindle 5 against turning on bolt 13, but when removing a completed cop and placing a fresh quill on the mandrel the 20 spindle and mandrel may be swung outward on bolt 13 into an accessible position.

On its rear side the yoke 6, is made with a fin 15 that is embraced by the forked arm 16, of a bell crank lever 17. The other arm of 25 lever 17 is pivotally connected with the member 181, forming part of the usual stop motion mechanism whereby the machine is automatically stopped when the yarn being wound breaks, or when the operation of 30 winding a cop is completed. Lever 17 is loosely mounted on bar 12 between two collars, 18, fixed to the latter. When the yarn breaks or when a cop is completed the member 181 is pulled toward the left, Fig. 2, and 35 acts through levers 16 and 17 and yoke 6 to lift the cop off from the driving drum 3 thereby stopping the winding operation.

The yarn or thread is led from the supply over a guide-bar 19, and through a thread 40 guide 20, to the cop being formed on spindle 5, thread guide 20 being slidably mounted on a bar 21, and reciprocated lengthwise of the cop by the usual cam, not shown.

During the winding operation the thread 45 guide 20 has a fixed region of movement that is, it continuously reciprocates in the same path in the usual fashion, but in my machine the continued addition of yarn to the cop that is being formed not only acts to 50 force spindle 5 away from drum 3 as the cop grows in diameter but it also acts through the cop and yoke 6 to swing link 8 on its pivot 9 and this movement of link 8 acts

to shift the spindle and the cop bodily endwise relatively to drum 3 and thread guide 55 20, in a direction toward the butt or large end of the cop. This endwise movement of the cop occasioned by the movement of link 8 is continuous during the winding operation and causes each spiral-connecting portion or strand of the yarn to be deposited on the butt of the cop by the thread guide 20 in a position just back or short of the spiral-connecting portion or portions onto which it is laid, with the result that the butt of the 65 cop is made up of superimposed spiral-connecting portions which occupy a shelled or receding relation so that the butt end of the 70 cop is crowned as shown at 22 in Fig. 3, and is free of floats or other imperfections. 75 The pivot 7 is preferably arranged just back of the middle point of spindle 5, and as will be clear this pivot permits the cop to at all times properly bed itself upon the cop driving drum 3.

The principle of operation of the machine will now be clear. The wedging action of the yarn as it is drawn between the driving drum and the cop tends to force the cop upward, but, owing to the fact that the yoke 6 is carried upon the end of swinging link 8, which is pivoted at its other end to one side and above the cop, the effort of the cop and yoke to move directly upward results in forcing the moving end of link 8, that is, the 80 pivot point 7, to move in a curved path, x , about the pivot 9, the effect of which is to 85 progressively shift the cop in the direction of its butt end as it grows in size and the spindle and yoke rise.

What I claim is:—

In a winding machine, a thread guide; a driving drum; a cop holder, a cop holder frame carrying the cop holder at the end of its free arm, the other arm being carried 95 upon the swinging end of a lever; that lever, pivoted to a fixed member on the frame to swing in the direction of the butt of the cop parallel with the axis of the cop as the cop grows and swings the cop holder frame up. 100

Signed by me at Westfield, Mass., this 4th day of August, 1913.

JOHN OLIPHANT McKEAN.
